FIG. 8

UNITED STATES PATENT OFFICE.

OSCAR G. EDMOND, OF SPOKANE, WASHINGTON, ASSIGNOR OF ONE-HALF TO WHITE PINE SASH COMPANY, OF SPOKANE, WASHINGTON.

RELISHING MACHINE.

Application filed August 23, 1924. Serial No. 733,712.

To all whom it may concern:

Be it known that I, OSCAR G. EDMOND, a citizen of the United States, residing at Spokane, in Spokane County, and State of Washington, have invented certain new and useful Improvements in Relishing Machines, of which the following is a specification.

My present invention relates to improvements in relishing machines adapted especially for use in the manufacture of window and blind sash for cutting or relishing two of the sash rails by a single operation of the machine tools.

The primary object of the invention is the provision of an improved mechanism that is adapted to cut away complementary edges of a pair of spaced tenons or tongues on the sash rail to insure correct jointing of the rails in subsequent assemblage of the window sash.

The relishing of two rails is accomplished by the use of a single rotary cutter and a pair of boring bits operating simultaneously on the two adjoining tenons for making a clear and clean cut without danger of tearing, splitting or otherwise marring the wood.

The machine of my invention involves mechanism for feeding the rails in a line across the machine top, and mechanism for detaining two aligned rails at predetermined periods. Means are also provided for separating the pair of rails preparatory to the action of the machine tools, and after the relishing operation the completed rails are ejected from the machine. The relishing tools are located beneath the path of travel of the line of rails and the tools are automatically reciprocated into operative position and out of operative position with relation to the rails. The invention consists in certain combinations and arrangements of parts whereby the machine operates automatically with rapidity and accuracy for accomplishing its purpose, as will hereinafter be more fully set forth and claimed.

In the accompanying drawings I have illustrated one complete example of the physical embodiment of my invention wherein the parts are combined and arranged in accordance with the best mode I have thus

far devised for the practical application of the principles of my invention. It will be understood however that changes and alterations may be made in the exemplified structure within the scope of my claims without departing from the spirit of my invention.

Figure 1 is a view in side elevation of a machine embodying my invention and disclosing particularly the power transmission mechanism.

Figure 2 is a view in elevation of the machine at the opposite side from Figure 1, part being broken away for convenience of illustration.

Figure 3 is a top plan view of the machine showing a pair of aligned rails being fed thereto.

Figure 4 is a horizontal view in cross section through the machine top and illustrating the means for adjusting the feed chains.

Figure 5 is a transverse vertical sectional view of the machine at line 5—5 of Figure 3.

Figure 6 is a diagrammatic view in perspective showing the relation of the relishing tools to the tenons of adjoining rails.

Figure 6^a is a perspective view at the tenon end of a rail after the relishing operation.

Figure 7 is an enlarged top plan view of the mechanism for detaining the rear rail and advancing the front rail of a pair preparatory to the relishing operation.

Figure 8 is a view with parts in section showing the mechanism of Fig. 7 in elevation.

The machine is provided with the usual main frame 1 for supporting the operating parts thereof, and is fashioned with a flat top 2 which projects outwardly therefrom toward the feed or front end of the machine. The power shaft 3 is journaled in suitable bearings 4 near the bottom of the main frame and is disposed transversely of the machine, that is at right angles to the travel of the sash rails as R and R'. The power shaft is provided with the usual tight and loose pulleys 5 and 6 and the power belt 7 connected to a suitable source of power drives the shaft continuously while the machine is in operation.

The sash rails R and R' are fed successively in close alignment across the top of

the machine from left to right and in Figure 1, by means of a pair of endless feed chains 8 and 9 which grip the rails at opposite sides thereof. The working flights of the chains travel in the same direction and are of sufficient length to grip a pair of rails as they are fed therethrough. A conveyer belt 10 with its upper flight located on a level with the table top is provided at the front of the machine and operated on suitable pulleys as 11, to supply rails to the feed chains. At the sides of the upper flight of the conveyer belt are arranged guide rails 12 which together with the belt form a trough through which the rails are guided to the feed chains.

To adapt the feed chains to various thickness of sash rails they are laterally and relatively adjustable on the table or machine top, and the chains are also adjustable longitudinally to compensate for wear and to secure the proper tension on the working flights.

Each feed chain is provided with a longitudinally extending frame or guide plate as 13 and 14, resting on the machine top 2. At their sides the respective plates are fashioned with upright flanges 15 for guiding the outer and inner flights of the chains, and on the bottom of each plate is a threaded boss 16 projecting through a transversely extending slot 17 in the machine top beneath the plates. There are two bosses 16 on each plate spaced apart and the bosses 35 on one plate are alined with the complementary bosses on the other plate as in Figs. 3 and 4 in order that the relative position of the two feed chains may be correctly adjusted by manipulation of four screw bars 18. These bars are arranged transversely of the machine and chains in alined pairs and at their outer ends the bars have hand wheels 19 for turning them in their bearings 20 in the side flanges 21 of the machine top 2.

Each chain has a driving sprocket wheel as 22 and 23 on vertical feed shafts 24 and 25 journaled in bearings 26 of the machine frame, and these shafts are driven from a countershaft 27 through bevel gear couples 28. The countershaft 27 is operated from the power shaft 3 by means hereinafter described.

Idler sprockets 29 and 30 for the chains 55 8 and 9 are journaled in brackets 31 which are slotted at 32 and adjustably connected to the plates 13 and 14 by means of the two pairs of bolts 33, and it will be apparent that the bearing brackets 31 of the 60 wheels 29 and 30 may be adjusted relatively to the plates for tightening or loosening the chains 8 and 9 on their pairs of supporting sprocket wheels, and to compensate for wear of parts.

The two adjoining working flights of the

chains grip the rails at opposite sides thereof and move in the same direction to present an alined pair of rails R and R' to the relishing tools. The rails are fed in a row intermittently and two of the rails are 70 relished by the machine tools while the rails are detained or at rest. The relishing tools reciprocate into and out of operative position synchronously with the feed movement of the rails. The rails are advanced 75 by the frictional engagement therewith of the feed chains and are positively held or retained for the operation of the relishing tools, while the feed chains continue to move relatively to the rails. The friction 80 between the chains and rails is sufficient to move the rails while they are free to advance, but the chains slide past the rails while the latter are detained. In their advance toward the relishing tools the rails R and R' pass under and are held down on the machine top by means of a leaf or plate spring 34 attached to the upper frame 35 which is bolted on the top of the machine frame.

The relishing tools comprise a pair of spaced boring bits 36 and 37 and an intermediate rotary cutter head 38 arranged in a line parallel with the line of travel of the rails, as indicated in Figure 6.

The relishing tools are located beneath the machine top and the rails are moved across the machine top with their adjoining tenons T in position for operation thereon of the relishing tools, the cut away portion of the tenons being indicated by dotted lines in Figure 6 and in full lines in Fig. 6a.

The rear rail R of a pair of rails is positively detained or stopped with its tenon in position for action of the boring bit 37 and cutter head 38 and then the front rail R' is relatively advanced a distance as indicated in dotted lines in Figure 8 to bring the tenon of this rail in position for action of the boring bit 36 and cutter head 38.

For detaining the rear rail R a laterally swinging or oscillatable detent 39 is adapted to engage the shoulder of the rail at the junction of the tenon and rail and hold the latter during the relishing operation, and after the operation the detent is swung out of the path of the cut rail. This detent is carried by a longitudinally slidable rock shaft 40, and secured thereon in adjusted position by its sleeve 41 and set bolts 42. The rock shaft is elevated above the rails and journaled in bearings in flanges 43 of the upper frame 35, and an expansion spring 44 coiled about the shaft is interposed between one of the flanges 43 and an anchoring pin 45 on the shaft. This spring serves the two functions of oscillating the shaft to return and hold the detent in operative position, and the spring also slides the shaft on its longitudinal axis to retract

the shaft. The spring 44 normally holds the shaft 40 with its detent 39 in stop position as indicated in Figure 8, and the detent is positively pushed out of stop position to permit movement of the relished rails by means of a slidable release tappet or push plate 46 in Figs. 7 and 8. This tappet is disposed at right angles to the axis of the shaft 40 and is slotted at 47 and retained on the upper frame 35 by means of bolts 48 which permit reciprocating movement of the tappet plate. This release tappet is actuated by means of a release lever 49 having its upper end pivoted at 50 (Fig. 5) in the upper frame 35, and the lever depends down through the slotted machine top. As the lever is actuated to swing on its pivot (in manner to be described) the tappet plate is pushed thereby over against the detent to rock shaft 40 and swing the detent out of the path of the relished rail. When the release lever is withdrawn the tappet or push plate is returned to retracted position by action of the detent as it swings with its rock shaft under action of spring 44.

The front rail R' is advanced with relation to the rear rail R by means of a hook 51 which is pivoted on a longitudinally slidable bar 52 at 53. This bar is located on the upper plate 35 parallel with and directly beneath the rock shaft 40 with the hook 51 in position to engage the rear end of the rail R', and the hook is held down to working position by means of a leaf spring 54 attached thereto and bearing up against the underside of the shaft 40. The bar 52 is slidable and guided in slots in the flanges 43 of the upper frame plate 35, and it is moved on its working stroke against the tension of a return spring 54' connected at one end 55 to the bar and anchored at its other end to a bracket 56 of the upper frame 35.

The forward working stroke of the bar 52 and its hook 51 is positively accomplished by means of a tappet arm 57 which extends laterally from the bar in the rotary path of movement of a roller 58 carried at the underside of a cam disk 59 located to revolve in a horizontal plane above the frame plate 35. With each revolution of this disk in the direction of the arrow in Fig. 7 the roller and tappet arm are brought into contact to slide the bar and hook longitudinally for a working stroke, and the return movement of the bar and hook is accomplished by the retracting spring 54'. The nose of the hook 51 is rounded to permit the following rail to contact therewith and lift the hook against tension of spring 54 and allow the forward movement of a relished rail.

The disk 59 is carried at the upper end of a vertical cam shaft 60 journaled in bearings 61 of the machine frame. This shaft revolves constantly and the intermittent en-

gagement of the roller 58 and tappet arm 57 is actuated by the longitudinal movement of the slide shaft 40 as follows.

The cam disk 59 which is loose on the shaft 60 is retained between an upper friction clutch member 62 and a lower friction clutch member 63 which members constantly rotate with the shaft. These constantly rotating clutch members engage the disk with sufficient friction to revolve the latter when it is free to revolve, but the members slip over the disk when the latter is detained.

The disk is normally held against rotation by means of a cam roller 64 engaging a recess 65 in the periphery of the cam disk. This roller is carried at the end of one arm of a bell crank lever 66 pivoted at 67 to the upper frame plate 35, and a spring 68 engaging the bell crank lever tends to hold the roller in its recess 65.

On the upper face at the end of the other arm of the bell crank lever is carried an anti-friction roller 69 and located in the path of movement of a cam trigger 70 carried by the longitudinally reciprocable shaft 40. The trigger is pivoted at 71 in a transverse slot 72 of the shaft and has a spring 73 tending to force it through its slot, but a shoulder or stop 74 on the trigger engages a notch or groove 75 in the shaft to prevent excess movement of the trigger.

It will thus be seen that as the advancing rail R engages detent 39 the shaft 40 is moved to the left in Figs. 7 and 8. During this movement the projecting trigger 70 encounters the roller 69 and swings the bell crank lever 66 on its pivot 67 to release roller 64 from its recess 65 in the cam disk 59. The released disk is now free to revolve with its clutch members 62 and 63 on the shaft 60 and the roller 58 strikes the tappet arm 57 to slide the bar 52 to actuate the hook 51 and advance the front rail.

The three vertical shafts 76 77 and 78 of the boring bits 36 and 37 and the rotary cutter 38 are carried in a vertically reciprocable cross head 79, which is slidable in fixed grooved frame 80 located below the machine top, and this cross head is retained against upward movement by means of a locking lever 81 (Fig. 2) having a retaining hook 82 adapted to engage over an anti-friction roller 83 on the cross head. The lever is pivoted at 84 on the cross head 80, and a spring 85 attached to the main frame of the machine and bearing on the edge of the lever tends to hold the hook over the roller.

At a predetermined time for lifting of the cross head, the hook is withdrawn from the roller by action of a tappet bolt 86 (Figs. 7 and 8) carried by the reciprocable spacing bar and hook 51. The upper end of this release lever 81 or locking lever is located in the path of movement of the tappet bolt and as the spacing hook 51 moves

to the left in Fig. 8 said tappet bolt contacts with the upper end of the locking lever and swings said lever to the left, with drawing hook 82 from the roller 83 to release the cross head and permit its upward movement to bring the relishing tool in operative position with relation to the spaced tenons of the sash rails.

The several shafts of the relishing tool frame are vertically slidable in fixed journal bearings 87 of the rectangular tool frame 80, and the shafts also have a sliding movement in the gears 88 89 and 90 respectively, which gears are keyed to revolve with their respective shafts 76 77 and 78 and are in mesh at all times.

Power is transmitted to the shaft 78 of the relishing tool frame from power shaft 3 by means of a bevel gear 91 on the latter shaft 20 and a pinion 92 on the shaft 78 for revolving the three members of the relishing tool.

The cross head 79 is vertically reciprocated to lift the relishing tool frame to operative position and to withdraw the same from operative position, by power also transmitted from the shaft 3, through pinion 93 on the latter shaft and a larger gear 94 on the clutch shaft 95 located above the power shaft 3 and parallel with the latter. The clutch shaft is journaled in bearings 96 of the main frame and is provided with a clutch 97 (Fig. 5) that is manually controlled through manipulation of either of the crank handles 98 or 99 at the ends of a crank shaft 100 disposed longitudinally of the machine and supported in bearings in the main frame of the machine. The operation of the machine is thus manually controlled by manipulation of either of these two crank handles.

Above the clutch shaft 95 is located an operating shaft 101 journaled in bearings 102 and provided with a large, loose sprocket wheel 103 for the sprocket chain 104. A friction clutch 105 on this shaft 101 permits free rotation of the sprocket wheel 103 while the hook 82 holds the lever 81 in locked relation to the cross head. When the lever is moved and the hook freed from the roller 50 to unlock the cross head the clutch engages with the sprocket wheel with sufficient friction to revolve the latter and the operating shaft 101 for the upward movement of the cross head 79 and its relishing tool.

The operating shaft 101 carries at one end a disk 102', and rotary movement of the shaft and this disk is converted into reciprocating movement of the cross head through the interposition of an eccentric 60 103' having a pin connection at 104' to the disk. The eccentric link is slotted at 105' for varying the length of its throw or stroke. The eccentric link is also connected by a pin as 106 to a lug 107 of the cross head, and 65 an arcuate slot 108 in the link also provides

for adjusting the throw of the eccentric link to regulate the predetermined movement of the cross head.

For regulating the movement of the cross head through the eccentric link, the latter 70 may be changed as to its position with respect to the disk 102' through manipulation of a hand wheel 109 and screw bar 110 (Figs. 1 and 2) which latter is connected at 75 111 to the eccentric link, and in this manner the relish of the tenons T indicated by dotted lines in Fig. 6 may be predetermined and fixed.

The push lever 49 is actuated from shaft 101 by means of a cam disk 49' on this shaft 80 and a cam lug 50' carried at the lower free end of the lever co-acts with the regulating disk to swing the lever on its pivot 50 and push the slide plate or tappet plate 46 as previously described.

The sprocket chain 105 as seen in Figure 1 is driven from the shaft 95 by means of a sprocket wheel 112 on said shaft, and this chain is provided with a double loop, one of which passes around a sprocket wheel 113 on the shaft 27 to actuate the feed chains 8 and 9. Another loop of this sprocket chain passes around a sprocket wheel 114 on the shaft 115 located at the opposite side of the wheel 112. This horizontal shaft 115 has a 90 bevel gear couple 116 for transmitting power to the vertical cam shaft 60.

The conveyer belt 10 is driven from the shaft 27 by means of a pulley 117 on the latter shaft, and a crossed belt 118 and pulley 119 on the shaft 120.

After the adjoining tenons of the pair of sash rails have been relished by the operation of the machine tools the completed rails are discharged at the rear end of the machine, 105 i. e. at the right in Figs. 1 and 3. As they are discharged through the pushing action of the feed chains these completed rails are guided against a guide rail 121 by a spring 122 as seen in Fig. 3. The guide rail extends longitudinally of the machine and is integral or rigid with a transversely disposed slotted bar 123 which is held to the machine top in adjusted position by means of a pair of bolts 124. A hand wheel and screw bar 125 are employed to advance the guide rail or to withdraw it, as required, toward and from the longitudinal center of the machine to adapt it for different widths of sash rails. The spring 122 at the side 110 of the sash rail opposite to the guide rail is carried by an adjustable slotted bar 126 which is retained on the machine top by bolts 127. The spring thus provides for a 115 resilient pressure against the sash rail to hold it against the guide rail, and the tension of the spring against the rail may be varied by manipulating a hand wheel and screw bar 128 to move the slotted bar 126 120 transversely of the machine top.

The upper frame 35, which supports the stopping and spacing devices for the rails is vertically adjustable above the top of the sash rails to compensate for variations in the height of the sash rails as they pass through the machine. The plate 35 of the frame is slotted as required to accommodate the operating parts of these devices and this plate has a vertical wall 129 with a laterally projecting, horizontal, threaded boss 130 for a complementary, vertically disposed screw bar 131.

The screw bar at its upper end has a hand wheel 132 and is journaled to revolve in a frame-head 133 bolted to the machine top. This fixed head 133 has spaced, vertical dovetail guides 134 and the adjustable frame has complementary guide grooves 135 (Fig. 7) for guiding and retaining the frame with relation to the frame head.

A housing 136 is fashioned under the machine top about the relishing tool frame when the latter is in operative position, and a draft pipe 137 is connected to said housing to convey to a suitable destination the dust and shavings from the relishing tool.

The machine as thus described is automatic in its operation from the time the rails are fed in a line from the conveyer trough to the feed chains and continued across the machine to the delivery, or discharge end. The several operating parts are inter-related and timed as to their operation in synchronism with other parts and the rails are fed and intermittently stopped, then spaced apart, and while in this stationary spaced position the tenons of the adjoining rails are relished. At the completion of the relishing action the relishing tools, which have previously been lifted to operative position, are withdrawn, the retained rails are released and successive rails are brought into position for relishing, at the same time forcing or pushing forward the completed rails.

The period of time required for operation of the relishing tool on the tenons is slight, and the halt or stopping of the line of sash rails for the relishing operation is therefore very short, thus permitting a rapid and at the same time an accurate performance of all the functions of the machine.

Having thus fully described my invention, what I claim as new and desire to secure by Letters Patent is—

1. In a relishing machine the combination with a continuous feed mechanism adapted to move a line of rails, of means for detaining a pair of rails, means for separating said rails, a relishing tool adapted to operate on the separated detained rails, and means for releasing the pair of detained rails.

2. In a relishing machine the combination with a pair of complementary endless feed chains adapted to move a line of rails, of

means for detaining a pair of rails, means for spacing said pair of rails, a relishing tool for operation on the spaced detained rails, and means for releasing the relished rails.

3. In a relishing machine the combination of a pair of relatively adjustable continuously moving endless feed chains adapted to move a line of rails, of means for detaining a pair of rails, means for spacing said pair of rails, a relishing tool adapted to operate on the spaced detained rails, and means for releasing the relished rails.

4. In a relishing machine the combination with a continuous feed mechanism adapted to move a line of rails, of a vertically adjustable supporting frame, means for detaining a pair of rails supported on said frame, means for spacing the pair of rails supported on said frame, a relishing tool adapted to operate on the spaced detained rails, and means for releasing the relished rails.

5. In a relishing machine the combination with a pair of relatively adjustable continuously moving feed chains adapted to move a line of rails, of a vertically adjustable supporting frame, means supported on said frame for detaining a pair of rails, means supported on said frame for spacing the pair of rails, a relishing tool adapted to operate on the spaced detained rails, and means for releasing the relished rails.

6. In a relishing machine the combination with feed mechanism, of an adjustable supporting frame, means on said frame for detaining a pair of aligned rails, means on said frame for spacing the pair of rails, and a relishing tool adapted to operate on the detained spaced rails.

7. In a relishing machine the combination with a pair of relatively adjustable continuously moving feed chains adapted to move a line of rails, of a vertically adjustable supporting frame, means supported on said frame for detaining a pair of rails, means supported on said frame for spacing the pair of rails, a relishing tool adapted to operate on the spaced detained rails, means for releasing the relished rails, and resilient guide mechanism for guiding the relished rails from the machine.

8. In a relishing machine the combination with feed mechanism adapted to move a line of rails, of means for detaining a rear rail of a pair and means for spacing the front rail therefrom, and a relishing tool adapted to operate on the detained spaced rails.

9. In a relishing machine the combination with feed mechanism adapted to move a line of rails, of means normally located in the path of movement of the line of rails for detaining the rear rail of a pair, means for engaging the front rail of this pair for spacing it from the rear rail, a relishing tool

adapted to operate on the detained spaced rails, and means for releasing the relished rails.

10. In a relishing machine the combination with a longitudinally slideable rock shaft and retracting means therefor, of a detent on said shaft and means on the shaft for normally holding said detent in the path of a rail, a relishing tool and means 10 for elevating said tool to operative position, means actuated by the longitudinally slideable shaft for releasing the elevating mechanism, and means for releasing said detent.

11. In a relishing machine the combination 15 with a relishing tool and means for elevating it to operative position, means for locking said tool in inoperative position, a longitudinally slideable rock shaft and retracting means therefor, means actuated by 20 said rock shaft for releasing the locking means, a detent on said shaft for engaging a rail, and means for releasing said detent.

12. In a relishing machine the combination 25 with a relishing tool and elevating means therefor, and means for locking said tool in inoperative position, of a longitudinally slideable rock shaft and retracting means therefor, means actuated by said rock shaft for releasing the locking means, a 30 detent on the rock shaft for engaging a rail, a spring on said shaft for holding the detent in operative position, and means for moving said detent to release a rail.

13. In a relishing machine the combination 35 with a longitudinally slideable rock shaft and a spring thereon for retracting said shaft as to both its longitudinal and rocking movement, of a detent on the shaft adapted to detain a rail, and means for moving 40 said detent to release a detained rail.

14. In a relishing machine the combination with a relishing tool and control means therefor, of a rail detaining device actuated

under pressure from a rail, a spacing device 45 coacting with the detaining device, and power transmission means actuated by the pressure-actuated detaining device for actuating the spacing device.

15. The combination with a longitudinally slideable rock shaft having a detent 50 thereon and a complementary slideable bar having a pivoted spacing hook thereon, of a rotary control device for co-action with the slideable bar, means for normally retaining said control device, and means carried by 55 the longitudinally slideable shaft for releasing said retaining means.

16. The combination with a longitudinally slideable rock shaft having a detent 60 thereon and a complementary slideable bar having a pivoted spacing hook thereon, of a rotary control device for co-action with the slideable bar, a bell crank lever for normally retaining the rotary control device, and means carried by the shaft for actuating 65 said lever to release the rotary control device.

17. The combination with a longitudinally slideable rock shaft having a detent thereon and a complementary slideable bar having a 70 pivoted spacing hook thereon, of a rotary cam disk having a roller thereon and a tap- 75 pet member carried by the bar in the path of movement of said roller, a bell crank lever for normally retaining the rotary cam disk, and a trigger device carried by said rock shaft for actuating said lever.

18. The combination with a detaining device of a slideable bar having a pivoted spacing hook thereon, and power-transmitting mechanism between said detaining device and slide bar for actuating the slide bar as described.

In testimony whereof I affix my signature.

OSCAR G. EDMOND.
